UNITED STATES PATENT OFFICE.

ROBERT J. EMORY, OF NEWARK, NEW JERSEY, ASSIGNOR TO BAIRD MOTION PICTURE MACHINE CO., A CORPORATION OF NEW JERSEY.

FILM-GATE MECHANISM FOR KINETOSCOPES.

1,257,593.

Specification of Letters Patent. Patented Feb. 26, 1918.

Application filed February 25, 1914. Serial No. 821,023.

To all whom it may concern:

Be it known that I, ROBERT J. EMORY, a citizen of the United States, residing in Newark, in the county of Essex and State 5 of New Jersey, have invented certain new and useful Improvements in Film-Gate Mechanism for Kinetoscopes, of which the following is a specification.

The invention relates to means for holding 10 the film in fixed position with respect to the aperture plate when the intermittent sprocket is at rest, and relates particularly to holding means which is automatically adjustable, to permit travel of the film without tearing or mutilation.

One of the main objects of my invention is to provide a device that cannot drag or travel with the film and which holds the film in an absolutely stationary position with 20 respect to the aperture plate when the intermittent sprocket is at rest.

A further object of the invention is to provide a device in which inequalities or variations in thickness on opposite edges of 25 the film are automatically compensated for and which will not bind or tear the film.

A still further object of the invention is to provide a device in which the maximum tension against the film can be readily adjusted and in which all of the parts will be 30 accessible for immediate inspection or repair.

The various other objects of the invention will in part be obvious from an inspection of 35 the drawings, and in part will be more fully set forth in the following description of one form of mechanism embodying the invention which consists in the new and novel features of construction and combination of 40 parts hereinafter set forth and claimed.

In the accompanying drawings:

Figure 1 is a side elevation of a kinetoscope embodying my improvement;

Fig. 2 is an enlarged front view of the 45 holding device;

Fig. 3 represents a side elevation in section of the device;

Fig. 4 represents a cross-section on the line 4—4 of Fig. 2;

50 Fig. 5 is a detail view showing the spring supports for the lower shoes;

Fig. 6 is a detail view showing the tension springs for the tilting shoes; and

Fig. 7 is a detail view showing the means for securing the holding device in engagement with the aperture plate.

Referring to the particular embodiment of my invention shown in the accompanying drawings, the aperture plate 1 is rigidly supported on the frame of the machine in 60 any suitable manner and is provided with a flat bearing face to support the edges of the frame. The gate mechanism is supported in proper position with relation to the aperture plate preferably on a door 2 65 hinged as at 3 to the frame of the machine so that it can be opened to give independent access to the aperture plate and adjacent parts of the machine and also give access to the gate mechanism.

The gate mechanism comprises essentially a pair of shoes 4 spaced to engage opposite edges of the film to hold same against displacement with respect to the aperture plate. Each of said shoes is pivoted by means of a pin 5 intermediate its ends to an eye 6 in the outer end of a sliding rod 7 mounted in a bearing 8 provided in the door. The shoes preferably comprise flat bearing faces 9 and flanges 10 provided with the pins 5, thus 80 permitting ready attachment to the eyes in the rod 7. These rods are free to reciprocate in their bearings in a line substantially perpendicular to the film and aperture plate.

The shoes are normally pressed outward 85 and into engagement with the film and aperture plate by means of a tension member comprising a plate 12 and spring arms 13 formed integral with the plate, or a separate piece secured thereto, and extending from 90 opposite corners of the plate. Each arm has a yoke or slot 14 in its end engaging with one of the rods between its socket and attached shoe. Said plate is provided, in the medial line thereof between the spring arms, with a 95 bearing socket or recess 15 which engages with a projecting stud 16 on the door. In this particular instance the socket is hemispherical in section, and the stud has a rounded head 17 seated therein so that the 100 plate is free to tilt or turn in any direction and is also centered and partly supported by

the stud. Below the plate is a bolt 18 provided with trunnions 19 slidingly mounted in grooves 20 formed in a boss 21 on the door. This bolt is provided with a pin or extension 22 having a curved bearing surface that engages the side of the plate opposite the socket approximately in the medial line of the plate, and, owing to its curved line of engagement, forms a swivel connection 10 with said plate. The bolt is moved inwardly or outwardly on its trunnion by any suitable means, as an adjusting nut 23 on the outside of the door to regulate the tension with which the shoes are forced outward and 15 against the film.

Arranged in line with the rocking shoes 4 are the tension shoes 25, each of which is mounted on one end of a spring arm 26 that is rigidly secured by any suitable means to 20 the back of the center plate 27. This plate is carried by a head 28 integral with the door between the spring arms 13, and is directly opposite the aperture plate and spaced therefrom when the door is closed. Said 25 shoes are relatively short and are rounded at their ends, permitting the film to pass readily and are held only under sufficient tension to prevent any back-lash of the film due to the sudden and intermittent stopping 30 of the sprocket wheel.

The door or movable part upon which the holding gate is mounted is held in normal working position with respect to the aperture plate by any suitable means, as a 35 spring lock 29 that engages behind the aperture plate when the door is closed. Said lock is disengaged by any suitable means as the pin 30 operated by the thumb nut 31. When in this position, the shoes are pressed 40 outward by the spring plate so as to engage the film and hold same firmly but yieldingly against the aperture plate. The shoes not only have a bodily movement against the tension of the spring allowed by reciprocation 45 of the rods 7 in their sockets, but also have a tilting movement on the pivot pins 5 and consequently varying thicknesses of film as well as inequalities on opposite sides of the film are automatically accommodated. 50 Furthermore, the tension plate has a swivel movement on the fixed stud or abutment 16 and with respect to the pin 22 permits equal bodily movement of the two shoes and compensates for inequalities on the opposite 55 sides of the film and tends to equalize the tension on both sides, thus preventing the film from being torn. The bodily movement of the shoes is accomplished gradually by a wedging movement as the film is drawn 60 downward and the point of maximum thickness in the film approaches the pivotal point of the shoe which is in line with the axis of the reciprocating rod.

By means of my construction, the adjustments 65 of the shoes to varying film conditions

are brought about gradually and with such balancing and equalizing of pressure between the two shoes that films in torn or damaged condition or which have been poorly or unevenly repaired can be used 70 without fear of further damage and without any decrease in the speed of operation of the machine.

It is obvious that the shoes 25 may be omitted entirely from the organization illustrated but their use in connection with the new form of rocking shoes 4 has the advantage of lessening the shock on the shoes 4 thereby tending to improve the registration 75 of the film in the picture aperture. 80

It will also be obvious that the invention embodies various other advantages not specifically set forth and that various changes may be made in the mechanism herein shown and described which are within the skill of 85 the mechanic and which are within the scope of my invention provided the means set forth in the following claims be employed.

Having thus described my invention, I 90 claim:

1. In a device of the character described, the combination with a plate for engaging one side of a traveling film, of a film engaging shoe mounted to have a rocking movement and independent bodily movement toward said plate and means for yieldingly holding the shoe in predetermined position. 95

2. In a device of the character described, the combination with an aperture plate of a sliding support, movable relative to said plate, of a shoe pivoted to said support intermediate its ends and movable with the support, and a bearing for said support permitting the sliding movement thereof in said bearing. 105

3. In a device of the character described, the combination with an aperture plate, of a shoe operatively mounted to hold the film relative to said plate, and a movable support for said shoe, and a tension spring connected 110 to said shoe, of an adjustable support for said spring, said support being mounted to permit tilting movement thereof. 115

4. In a device of the character described, the combination with a carrying member, of a sliding support mounted on said member, a shoe pivoted to said support intermediate its ends and having independent rocking movement on said support, of a tension member comprising a spring engaging said 120 support, a carrying member for said tension member and a swiveled connection between said carrying member and said tension member whereby the latter is free to have a tilting movement relative to said carrying member. 125

5. In a device of the character described, the combination with a carrying member, of a sliding support mounted on said member, a shoe pivoted to said support intermediate 130

its ends and having independent movement relative to said slidable support, of a tension member comprising a spring engaging said slidable support, said tension member having a bearing on an abutment fixed relative to said fixed support and forming a universal joint, and means for positively moving the tension member on said abutment to adjust the tension of said spring.

5 10. 6. In a film gate mechanism, the combination with an aperture plate, a pair of supports slidably mounted relative thereto, a shoe pivoted to each support, a tension member comprising spring arms engaging each support and a plate secured to said spring arms, a fixed bearing and a movable bearing engaging opposite sides of said plate, whereby uneven tension on the springs automatically tilts said plate relative to said aperture plate.

15 7. In a film gate mechanism, the combination of a slidably mounted support, means for carrying said support, a shoe pivoted to said support intermediate its ends, a tension member comprising a spring engaging said support, and a plate supporting said spring, an abutment having a bearing in engagement with one side of said plate, and a movable adjusting member having a curved bearing surface engaging the opposite side of said plate, and means for adjusting said member.

20 8. In a film gate mechanism, the combination with a frame having an aperture plate thereon, a door pivoted to said frame and having a gate mechanism mounted thereon, said gate mechanism comprising two movable supports, and two pairs of shoes arranged in line with each other, one of said pairs of shoes being loosely pivoted to said movable supports to have independent rocking and bodily movements, and the other pair of shoes being yieldingly supported to have bodily movement with respect to the aperture plate.

25 9. In a film gate mechanism, the combination with an aperture plate and means for feeding the film relative to said plate, of a film gate comprising two pairs of shoes extending in the direction of movement of the film and in resilient engagement therewith,

and on the side thereof opposite the plate, the tension on one of the pairs being relatively constant and the tension of the other pair being variable.

55

10. 10. In a film gate mechanism, the combination with a frame comprising an aperture plate and means for feeding a film relative to said plate, of a door movable relative to said plate on the side of the film opposite said plate, a film engaging shoe carried by said door and movable therewith into engagement with the film to press the same into engagement with the aperture plate, a lever for controlling the engagement of said shoe with the plate, and means movable with the door for adjusting said lever from a position exterior of the door when the same is in closed position.

60

11. 11. In a motion picture machine, the combination with a plate adapted to engage one side of a traveling film, a shoe pivoted intermediate its length for movement about an axis transversely of the path of movement of the film and adapted to engage the other side of the film to press the same against the plate, said shoe mounted for bodily movement in a direction toward and away from said plate and resilient means continually engaging said shoe for moving the same toward said plate.

70

12. 12. In a device of the class described, means for holding a traveling film in position, said means including a pair of members designed to contain the film therebetween, one of said members providing a relatively fixed bearing surface designed to engage one side of the film and the other member having a resilient engagement with the opposite side of the film to force the same against said bearing surface and said other member mounted to have a rocking movement in the line of the travel of the film whereby irregularities of thickness in the film is caused to pass the holding means without affecting the film.

75

This specification signed and witnessed this 21st day of February, A. D. 1914.
